UNITED STATES PATENT OFFICE.

CHARLES OSBORNE, OF NEW YORK, N. Y., ASSIGNOR, BY MESNE ASSIGNMENTS, TO CARNEGIE HERO FUND COMMISSION, OF PITTSBURG, PENNSYLVANIA.

DESIGN FOR A MEDAL OR SIMILAR ARTICLE.

No. 38,343.

Specification for Design.

Patented Dec. 11, 1906.

Application filed October 10, 1906. Serial No. 338,325. Term of patent 14 years.

To all whom it may concern:

Be it known that I, CHARLES OSBORNE, a citizen of the United States, residing in the city, county, and State of New York, have invented a new, original, and ornamental Design for a Medal or Similar Article, of which the following is a specification, reference being had to the accompanying drawings, forming part thereof.

Figures 1 and 2 represent the obverse and

reverse views of a medal or similar article, showing my new design.

I claim—

The new, original and ornamental design for a medal or similar article as shown.

CHARLES OSBORNE.
